UNITED STATES PATENT OFFICE.

ERNST SCHMID, OF ANNECY, FRANCE.

RECIPROCATING ENGINE.

1,413,543.

Specification of Letters Patent. Patented Apr. 18, 1922.

Application filed December 17, 1919. Serial No. 345,630.

To all whom it may concern:

Be it known that I, ERNST SCHMID, a citizen of Switzerland, and residing at Annecy, Haute Savoie, France, have invented certain new and useful Improvements in or Relating to Reciprocating Engines, of which the following is a specification.

This invention relates to an improvement in or modification of the apparatus described in U. S. Patent No. 1,213,274 of January 23, 1917, for preventing leakage past the hollow spindle of the slide valve of an engine. This apparatus comprises an expansion chamber which surrounds the guide socket of the said spindle, and in which working fluid which has leaked into said chamber is stored during the compression, explosion and exhaust, and is subsequently restored to the same working cylinder during the suction period in that cylinder, through the said hollow spindle. The result of this arrangement is that the excess of pressure of the escaped gases in the expansion chamber over the surrounding pressure is maintained during the compression, explosion and exhaust periods.

The object aimed at by the present invention is completely to avoid the said excess of pressure in the expansion chamber of each of the several cylinders of an internal combustion engine.

This object can be attained by the means indicated by way of example in the accompanying drawing wherein Figure 1 is a longitudinal section of the upper part of an internal combustion engine, and

Figure 2 is a similar view of a modification.

By reason of the means shown the gases which escape into the expansion chamber of a cylinder at the moment when the explosion takes place in the cylinder are at once drawn into another cylinder by the suction produced at the same instant in this latter cylinder.

Take the case of a four cylinder engine: 1, 2, 3, 4 provided with water jackets; 7 designates a jacketed cover fixed into the cylinders; inside of said covers are screwed casings 8 closed by means of covers 9, the interior of each casing forming an expansion chamber 23. Each cylinder has slidably mounted in it an annular valve 12 adapted to alternately open and close the inlet and outlet ducts (not shown). Said valve is made with a cross bar 16 to which is con-

nected the rod 17 acting to move the valve and passing through sleeves 24 and 9^a integral with the casing 8 and the cover 9 respectively. Each rod 17 is made with an internal channel 19 and near the upper and lower parts thereof with ports 20 and 21. In the lowermost position of each rod 17, said ports 20 are positioned opposite the space 24^a between the sleeves 24 and 9^a whilst the ports 21 will communicate with the interior of the respective cylinder 1, 2, 3 or 4. At the instant explosion takes place in the cylinder No. 1, admission takes place in the cylinder No. 4. It is therefore sufficient to connect together the two corresponding expansion chambers 23 by a pipe 41. When the explosion takes place in the cylinder No. 1, working fluid escapes along the rod 17 and passes into the expansion chamber 23; it is immediately drawn by the cylinder No. 4 through the pipe 41 and the expansion chamber 23 into the said cylinder.

Conversely, at the instant when explosion takes place in cylinder No. 4, admission takes place in the cylinder No. 1 and the same thing happens as in the preceding case, but in the reverse direction. The same will be the case in the cylinders 2 and 3, the two expansion chambers of which will be for the same purpose connected together by a pipe 41^a.

It is advisable to make the arrangement so that the capacity of the passages of the two expansion chambers (of the pipe between the two cylinders) should be the same for each group of cylinders.

The arrangement shown by way of example for this four cylinder engine is applicable in the same way to an engine with six, eight, twelve, sixteen or any even number of cylinders.

Finally, it is pointed out that the same object could be attained by other means, for instance by connecting all the expansion chambers 23 to one and the same pipe 41 by respective branches such as 41^b, 41^c, as shown in Figure 2, the pipe 41^a being then omitted. The exhaust gases are thus maintained permanently at low pressure by the successive 105 suctions of all the cylinders.

Claims:

1. In a reciprocating engine, the combination, with a series of cylinders and valve rods passing through the walls of the respective cylinders, of respective expansion chambers surrounding the said valve rods and

adapted to receive and to allow expansion therein of gas escaping from the cylinders along the said rods, means for permanently connecting each of the said chambers to the 5 other expansion chambers, and means for periodically connecting each of the said chambers to the interior of the respective cylinder, for the purpose of allowing the gas contained in the said chamber and in the 10 chamber or chambers communicating with it, to be drawn from the said chambers into the said respective cylinders.

2. In a reciprocating engine, the combination, with a series of cylinders and valve 15 rods passing through the wall of the respective cylinders, of respective expansion chambers surrounding the said respective valve rods and adapted to receive and to allow expansion therein of gas escaping from the 20 cylinders along the said rods, of conduits permanently connecting each expansion chamber to the other expansion chambers, each valve rod for periodically connecting the respective expansion chamber to the interior of the 25 respective cylinder, for the purpose of allowing the gas in the said chamber and in the chambers communicating with it, to be drawn in through the respective valve rod into the said respective cylinder.

30 3. In a reciprocating engine, the combination, with a series of cylinders and valve rods passing through the wall of the respective cylinders, of expansion chambers surrounding the respective valve rods and 35 adapted to receive and to allow expansion therein of gas escaping from the cylinders along the said rods, of conduits permanently

connecting each expansion chamber to the other expansion chambers, each valve rod for connecting the respective expansion 40 chamber to the interior of the respective cylinder during the suction period, for the purpose of allowing the gases in the said chamber and in the chamber or chambers communicating with it, to be drawn through 45 the said valve rod into the said cylinder.

4. In a reciprocating engine, the combination, with a series of cylinders and valve rods passing through the wall of the respective cylinders, of expansion chambers enclosing the respective valve rods and adapted to receive and to allow expansion therein of gas escaping from the cylinders around the said rods, of means for connecting the expansion chamber of each of the cylinders, 50 to the expansion chamber of another of the said cylinders, which is at a different phase of working, each valve rod being provided with means for connecting the respective expansion chamber to the interior of the 55 respective cylinder during the suction period of the latter, for the purpose of allowing the gas in the said chamber and in the chamber communicating with it, to be drawn through the said valve rod into the said respective cylinder.

In testimony that I claim the foregoing as my invention I have signed my name in presence of two subscribing witnesses.

ERNST SCHMID.
